UNITED STATES PATENT OFFICE.

WILLIAM J. MYERS, OF TARRYTOWN, NEW YORK.

SCAFFOLD CLAMP.

Application filed May 2, 1923. Serial No. 636,270.

To all whom it may concern:

Be it known that I, WILLIAM J. MYERS, a citizen of the United States, and a resident of Tarrytown, in the county of Westchester 5 and State of New York, have invented a new and Improved Scaffold Clamp, of which the following is a full, clear, and exact description.

This invention relates to scaffold clamps 10 which may be secured to a beam of substantially any size and shape and act to support a scaffold on the beam at any desired height, the object of the invention being to provide a simple construction which will accomplish 15 these results with a minimum amount of effort on the part of the operator.

Another object of the invention is to provide a scaffold clamp of simple construction which may be quickly applied and re- 20 moved from a supporting beam or board in a substantially horizontal direction.

A still further object of the invention is to provide a scaffold clamp provided with 25 means for supporting a scaffolding joist and a plurality of automatically engaging spurs or edges for preventing slipping.

In the accompanying drawing—

Figure 1 is a perspective view of a clamp disclosing an embodiment of the invention. 30 Figure 2 is a longitudinal vertical section through the clamp shown in Figure 1 on a slightly enlarged scale, said clamp being shown in operative position.

Referring to the accompanying drawing by numerals, 1 indicates a supporting beam of any kind, as for instance, a two-by-four and 2 indicates a scaffolding joist for supporting the scaffolding boards 3. The reference numeral 4 indicates my improved 35 clamp, which may be used on a single upright or beam 1, as shown in Fig. 2, or it may be used to straddle a plurality of uprights to secure the necessary support for the scaffolding.

As indicated in Figure 1, the clamp 4 is provided with a pair of upright bars 5, a pair of upright bars 6, a pair of lower horizontal bars 7 and a pair of upper horizontal bars 8. The respective bars 7 and 8 are provided with connecting sections 9 and 10 of identical construction, each connecting bar being preferably formed integral with the respective bars 7 and 8 and constructed with a sharp edge 11 designed to cut or stick into the supporting beam 1 when the device 55 is in use. It will thus be seen that the upper

and lower bars 7 and 8, with their cross bars 9 and 10, form U-shaped structures, which structures are pivotally connected to the vertical bars 5 and 6 by suitable pivotal members, which members are preferably ordinary bolts, though some other form of pivot might be used. It will be noted that the clamp is open on one side, namely, on the side opposite the bars 9 and 10 whereby it 60 may be moved horizontally to a position straddling a support as shown in Figure 2 and then the joist 2 placed in position, which naturally will pull downwardly on the bars 6 and parts immediately connected 65 therewith so as to tilt the respective bars 7 and 8 and cause the edges 11 to dig into the supporting beam 1. At the same time that this occurs, the bars 6 will pinch the joist 2 against the supporting beam 1 and thereby co-act with the edges 11 for providing 70 a firm support for the joist 2 and the scaffolding boards 3.

It will be evident that this clamp may be mounted at any point along the supporting beam 1 so that the boards 3 may be arranged at any desired height. The beam 1 need not be fastened to anything but may be merely set upright and the parts assembled as shown in Figure 2. Where several 80 of these beams are used, a firm scaffolding will be provided which may be quickly and easily assembled or disassembled. This arrangement of clamp obviates the necessity 85 of using nails or other devices which will injure the supporting beam 1 and the joist 2. The beam 1 and joist 2, as well as the boards 3, may be used a large number of times as they are not injured by the clamp. The cross bars 9 and 10 may be of any desired 90 length and are preferably made of a length as wide as the usual supporting beam 1. If a narrow supporting beam 1 should be used, this will not prevent a proper action of the clamp so that an extra width of clamp is not objectionable but permits a clamp to be used on large or small supporting beams, boards and the like. 95

What I claim is:—

1. A scaffolding clamp, comprising a 105 pair of substantially U-shaped end members, four connecting bars pivotally connected at their respective ends with said U-shaped members in such a manner that the U-shaped members may swing on the various connections, said clamp being adapted to have the legs of the U-shaped members straddle a 110

support and the closed ends of the U-shaped members act as spurs when the device is in use.

2. A scaffolding clamp, comprising a pair of U-shaped end members, the closed ends of said members being sharpened on the inside so as to act as spurs, and a plurality of connecting members pivotally connected to both sides of said U-shaped members for forming a frame which may be collapsed, said frame being adapted to straddle

a support when the device is in use with the sharpened edges of the cross members of the U-shaped members engaging the support as spurs.

3. A scaffolding clamp, comprising a pair of U-shaped members, bars pivotally connecting the open ends of the members, and another pair of bars pivotally connecting the U-shaped members at points removed from their open ends.

WILLIAM J. MYERS.
